UNITED STATES PATENT OFFICE.

RALPH L. LEE, OF DAYTON, OHIO, ASSIGNEE TO DELCO-LIGHT COMPANY, OF DAYTON, OHIO, A CORPORATION OF DELAWARE.

WRINGER DRAIN BOARD AND CONVEYER.

Original application filed March 31, 1923, Serial No. 629,202. Divided and this application filed April 30, 1924. Serial No. 710,136.

The present invention relates to clothes wringers of the type having a conveyer for the clothes to be wrung and a drain board.

The present invention is a division of my copending application, Serial No. 629,202, filed March 31, 1923.

One of the objects of the invention is to eliminate the dropping of water from the wringer upon the floor by directing the water issuing from the wringer upon a drain board whence it is conveyed generally to the receptacle from which the clothes were taken.

Another object is to provide for the facile removal of the drain board from the wringer.

Further objects are to provide an endless belt conveyer for conveying clothes between the wringer rolls which can be moved into different operating positions, and which can be removed without disassembling the wringer; and to provide a conveyer belt which tends to remain in correct alignment with the wringer rolls and one which can be readily uncoupled to provide for removal thereof.

Further objects and advantages of the present invention will be apparent from the following description, reference being made to the accompanying drawings, wherein a preferred form of embodiment of the present invention is clearly shown.

In the drawings:

Fig. 1 is a sectional view of the wringer unit, the section being taken on line 1-1 of Fig. 2.

Fig. 2 is a sectional view taken on line 2-2 of Fig. 1.

Fig. 3 is a fragmentary perspective view of the drain board and conveyer showing the lock for maintaining the drain board and conveyer in either of its positions.

Referring to the drawings, the wringer 23 is secured by bolts 24 to a swinging bracket 20 and includes inverted U-shaped side frames 50 and 51 held together by bolts 52. Frames 50 and 51 may be considered half-shell portions, and each is provided with downwardly extending side walls 53 which form with the tops of the frames 50 and 51 a channel 53^a. Frames 50 and 51 are provided with inwardly extending ribs 54 which form guides for the roller shaft bearings 55 and 56.

Pressure or wringer rolls 68 and 69 are 55 carried by shafts 70 and 71, respectively. Shaft 70 bears downwardly upon the lower bearing 55 while the upper bearing 56 bears downwardly upon the shaft 71. Pressure between the rolls is supplied by a pressure 60 spring 72 located within the channel 53^a. Shaft 70 of the lower roll is connected with a suitable power device by a coupling 34.

The side walls 53 of the wringer frame members 50 and 51 extend downwardly to 65 enclose the bearings 55 and 56 and the ends of the rolls and to provide an opening for the introduction of clothes. By enclosing the gearing, coupling, and roll ends, danger to the operator and to the clothes is sub- 70 stantially reduced.

Drain board.

The lower end of the wringer 23 carries a pivotally mounted drain board 58, mounted between rails or side frames 59 and 60. Each rail carries a trunnion screw 61 rotatably and loosely journaled in larger holes 61^a provided in the branch portions of the wringer frame. Both trunnion screws 61 75 are removable endwise through the ends of the frame. To remove the drain board, the right-hand screw 61 (Fig. 1) is removed. Because of the looseness of fit between the screw 61 and hole 61^a, the board 58 can be 80 tilted until its right hand side clears the wringer frame. Then the board can be removed by sidewise movement without disassembling the wringer.

Drain board 58 is provided with a locking 90 device for maintaining the board in either of its operating positions. This locking device comprises a sliding pin 63 carried by the frame 50 (see Fig. 3). Pin 63 has a notch 64 formed by flattening off a side of pin 63. 95 A pin 65 inserted from the side of the frame 50 is received by the notch 64 and is adapted to cooperate with the ends of the notch to prevent the locking pin 63 from being pulled entirely out of the frame 23. Pin 63 cooperates with holes 66 and 67 in the side rail 60 so as to lock the drain board in either of its tilted positions.

The wringer unit is provided with devices tending to direct water dropping from the wringing apparatus toward the drain board so as to prevent splattering the floor. To accomplish this the wringer is provided with

water receiving ledges 113 extending under the ends of the lower roll 68 and over the drain board rails 59 and 60. Each ledge is provided with a drip flange 114 located above the drain board 58, the drain board 58 being cut away slightly as at 116 to provide clearance for said flange 114. Water tending to follow the shafts 70 and 71 drips off onto the ledges 113 and is directed by flanges 114 toward the drain board 58. The flanges 114 tend to divert water issuing endwise from the rolls toward the drain board. The drain board 58 is provided with drip strips 58^a tending to prevent water running back under the drain board toward the wringer frame and dripping upon the floor.

The drain board 58 provides a movable support for the movable wringer conveyer now to be described. At opposite end edges of the board 58 rails 59 and 60 carry rollers 95 and 96 located parallel to the pressure rolls 68 and 69, and adapted to support a conveyer belt 97 interposed between the wringer rolls 68 and 69 and therefore moved by the rotation of these rolls. Rollers 95 and 96 are tapered so as to be larger in diameter at the center than at the end in order that, during the movement of the belt, the belt will remain in alignment with the wringer rolls.

A series of spaced loops 101 are sewed to the one end of the conveyer belt 97 while spaced loops 102 are sewed to the other end of the conveyer belt. Loops 101 are adapted to fit within the spaces between the loops

102 while the loops 102 are adapted to fit within the spaces between the loops 101. A stave 103 is inserted into the loops 101 and 102 to thereby lace the belt. The construction of the conveyer belt 97 and the means for connecting the ends thereof to provide an endless conveyer is clearly shown and described in my copending application, Serial No. 710,163 filed April 30, 1924.

For the present invention it is sufficient to say that the stave 103 can be removed to disconnect the ends of the belt 97 whereby it can be removed from the drainboard.

While the form of embodiment of the present invention as herein disclosed, constitutes a preferred form, it is to be understood that other forms might be adopted, all coming within the scope of the claim which follows.

What I claim is as follows:

In a wringer, the combination with wringer rolls and a supporting frame; of a drain board movably mounted upon the frame and including a flat part and side members extending above the flat part; an endless belt conveyer passing between the rolls; and rollers mounted adjacent opposite ends of the drain board for supporting the belt, said rolls having flanges each adjacent an end of the roll and including the belt between them, the flanges extending partly below the upper edges of the side members.

In testimony whereof I hereto affix my signature.

RALPH L. LEE.
